UNITED STATES PATENT OFFICE.

ROBERT B. WOLF, OF NEW YORK, N. Y.

METHOD OF AND APPARATUS FOR BLEACHING PULP.

Application filed March 13, 1922. Serial No. 543,234.

To all whom it may concern:

Be it known that I, ROBERT B. WOLF, a citizen of the United States, residing at New York city, in the county of New York, State 5 of New York, have invented certain new and useful Improvements in Methods of and Apparatus for Bleaching Pulp; and I do hereby declare the following to be a full, clear, and exact description of the invention, such 10 as will enable others skilled in the art to which it appertains to make and use the same.

This invention relates to the bleaching of pulp or paper stock, and particularly to 15 a method of and apparatus for treating such material to more effectively accomplish the desired bleaching.

In the bleaching of paper stock it has been proposed heretofore to treat the material in apparatus including, for example, 20 a horizontal tank having a medial partition or midfeather about which the mixture of pulp and bleaching liquor is caused to sluggishly circulate by one or more transversely arranged propellers. Other forms of 25 apparatus have been used for this purpose. In all such apparatus the maximum permissible concentration of the pulp is approximately 6%, at which concentration the mass 30 is substantially fluid. This low concentration is necessary because of the difficulty otherwise experienced in maintaining the desired circulation. Moreover, the temperature of the mass must be relatively high, 35 e. g., 110° F. to ensure the desired bleaching action within a reasonable time.

Aside from the slowness of the bleaching operation which consumes approximately eight hours, the additional difficulty is presented that the relatively high temperature 40 tends to break down the cellulose, thus causing a greater loss in bleaching than would result from an operation conducted at a lower temperature. Furthermore, the dis- 45 colored fibres commence to bleach too rapidly on the outside and the bleaching solution is thereby prevented from penetrating the fibre and thoroughly bleaching the same.

I have discovered that the bleaching operation 50 may be more effectively conducted with several advantages, including those hereinafter set forth, by employing a mass of pulp and bleaching agent of much higher concentration than has heretofore been 55 practicable. Thus the mass may contain

from 10 to 25% of pulp, the concentration being such as to ensure a mass of comparatively stiff or non-fluid consistency. Such a mass may be bodily conveyed through the bleachers as contrasted with the 60 fluid circulation heretofore practiced. In the preferred embodiment of the invention, therefore, the mass of pulp and bleaching agent is mechanically advanced and periodically agitated to ensure thorough commingling of the pulp and bleaching agent. With the higher concentration of pulp a bleaching solution containing 20 to 30 grams of available chlorine per liter may be used. The operation may be conducted at a lower 70 temperature than heretofore, and shrinkage, which would otherwise result from the breaking down of the cellulose, is thereby avoided. As a result of operation in the manner described, it is possible to materially increase the effectiveness of bleaching operations so that a mass containing, for example, 18 to 20% of pulp may be successfully bleached in about three hours or less than half the time required under the old 80 practice using a mass containing not over 6% of pulp.

I have discovered also that the pulp may be advantageously delivered directly from the wet machine to the bleachers. This operation is particularly desirable inasmuch as it facilitates the removal of moisture to a degree which ensures a pulp mass of the desired concentration when the bleaching agent is added. In the wet machine the 90 pulp is preferably concentrated to about 25 to 30% and is delivered directly from the doctor to the bleachers where it is mixed with sufficient bleaching liquor to provide a mass containing, for example, 18 to 20% 95 of pulp. A plurality of bleaching tanks may be provided so that the capacity of the bleachers equals that of the wet machine.

As a result of the high concentration of pulp in the mass, there is a tendency to the 100 formation of "fish eyes," i. e., small globular bodies formed by the agglomeration of the fibre. These bodies, if permitted to remain, would interfere with the production of paper from the pulp. I have discovered, however, 105 that by dilution of the pulp and passage thereof over "riffles" the "fish eyes" may be entirely eliminated. The pulp is thus prepared for its utilization in the manufacture of paper.

In carrying out the invention, it is possible to employ bleachers of varying form and construction, but in the preferred embodiments of the invention apparatus is employed such as is hereinafter described.

This apparatus is illustrated in the accompanying drawings, in which,

Fig. 1 is a plan view of a bleaching apparatus;

Fig. 2 is a section on the line 2—2 of Fig. 1;

Fig. 3 is a side elevation of the same apparatus;

Fig. 4 is a plan view with the cover removed of another form of the invention;

Fig. 5 is a plan view of another form of the invention;

Fig. 6 diagrammatically illustrates the arrangement of the wet machine and the bleachers, whereby the pulp is delivered directly to the bleachers;

Fig. 7 is a plan view of another type of bleaching tank;

Fig. 8 is a vertical section through the structure illustrated in Fig. 7, and

Fig. 9 diagrammatically illustrates the arrangement of the "rifles" with reference to the bleaching apparatus.

In the accompanying drawings, I have illustrated an oblong tank having the vertical side walls 10, 11 and end walls 12, 13. Midway between the side walls there is a vertical partition or midfeather 14 which extends between the end walls 12 and 13 and around which the pulp is to be fed. At its ends, the midfeather is provided with large ports 15, 15. The tank, as thus described, may be formed of tile-lined Portland cement or other suitable material which will not be

affected by the action of the calcium bichlorite solution, and is preferably provided with a suitable cover. Within the ports 15 there are located flanged metal bushings 16. Extending axially through the two ports are shafts 17, 18, which are journaled in suitable bearings mounted in the side walls 10 and 11 of the tank and provided with stuffing boxes or other suitable devices to prevent leakage of the contents of the tank.

On the shafts 17 and 18 there are short worm propellers or agitators 19 and 20 which fit within the collar 16. The shafts 17 and 18 carry also reverse propeller blades 19' to prevent piling of the mass against the sides 55 of the tank. The ports 15 are located some distance below the upper edge of the midfeather so that the propellers are submerged in the contents of the tank. The shafts 17 and 18 may be driven in any suitable way, for example, by electric motors 21, 22, the shafts of which are connected to the shafts 17 and 18 by suitable power-transmitting mechanism. The motor shafts may, for example, have the small sprockets 23 from

65 which chains 24 extend to the sprocket

wheels 25 on the propeller-bearing shafts. If these shafts are driven in the same direction, the worm propellers are of opposite hand or pitch, but, if driven in the opposite direction as shown, the propellers are of the same hand or pitch, the purpose being to transfer the stock from one side of the midfeather and at the same time to effect thorough commingling of the fiber and the aqueous bleaching solution.

In accordance with the present invention for accomplishing the purposes which I have hereinbefore stated, I provide means extending longitudinally of the tank for mechanically conveying the stock in a closed path through the tank, as a result of which I am able to use a much more concentrated pulp mass which could not be successfully treated otherwise. Thus, in the lower part of each of the longitudinal compartments formed in the tank by the midfeather 14, I provide pairs of worm propellers of opposite hand, as clearly shown in Fig. 1. The worm propellers of each pair are indicated at 26, 27, and their shafts 28, 29 are journaled in suitable bearings in the end walls 12 and 13. The bottom of each compartment is preferably formed with semi-cylindrical grooves or beds 30, 31 to receive the worm propellers as shown in Fig. 2. The shafts 28 and 29 at one end project beyond the end wall 13 and are driven in any suitable manner. For example, I employ an electric motor 32, which through pinion 33 and gear 34, drives a shaft 35 having suitable driving connections 40 ccoperating with and driving worm gears 36 on the shafts 28 and 29.

The worm propellers or conveyers are rotated at relatively slow speed, those of each pair being rotated in opposite directions so as to feed the whole body of stock slowly around the midfeather and constitute with the material in which the conveyers are embedded a moving bottom of the two compartments of the tank upon which the bulk of the mass of pulp and bleaching agent is bodily transported. Shafts 17 and 18, on the other hand, are driven at relatively higher speed so that the fanlike propellers or short worms offer comparatively little resistance to the stock and yet furnish the necessary mixing or brushing action to thoroughly mix the bleaching reagent with the pulp. To assist in breaking up and more effectively mixing the pulp with the bleaching reagent, there is placed on one end of each of the shafts 28, 29 a short worm blade or propeller 37, 37₁. These short worm propellers 37, 37₁ are located at the end of the travel of the mixture of pulp and bleaching solution in each compartment and in the vertical transverse planes of the ports or openings 15. The conjoint action of the main propeller blades 26 on the shafts 28 and the short blades 37, 37₁ is to force the

stock upwardly when it reaches the end of the compartment and also to break up lumps of pulp.

Referring to Fig. 6 of the drawing, the wet machine is indicated at 59 and is supplied with pulp through a pipe 60. The wet machine is provided with rolls 61 and 62 and a traveling felt 63 supported on idlers 64 and adapted to convey the pulp to a doctor 65. The latter delivers the pulp to a trough 66 having a worm conveyer 67 therein. The trough is disposed with respect to one or more of the bleaching tanks so that the pulp may be delivered directly to the tanks as desired. This arrangement effects a material saving in the handling of the pulp and enables the production of a drier pulp and a more uniform mixture of the pulp with the bleaching liquor than is otherwise possible.

In operation, the pulp, for example, from the wet machine, and the bleaching liquor are fed into the tank in any convenient way and the various moving parts are set in operation. The longitudinally arranged worms are rotated slowly, say from 4 to 6 revolutions per minute, and the cross propellers or worms are driven at relatively high speed, say 50 to 100 revolutions per minute. The whole dense mass travels bodily through each compartment under the propelling action of the longitudinal worms, the cross worms agitating and mixing the pulp with the reagent as the mixture passes from one compartment to the other.

As hereinbefore noted, the treatment of the concentrated mass of pulp sometimes results in the formation of "fish eyes" in the mass. This difficulty may, however, be readily overcome. Referring to Fig. 9 of the drawing, a bleaching tank 68 is diagrammatically illustrated, the tank being provided with means such as longitudinal worms 69 to advance the body of pulp there-through and with transversely-disposed worms 70 for the purpose of agitating the pulp. The pulp in this tank is relatively concentrated, e. g., 18%. At the conclusion of the bleaching operation, the pulp is discharged through a pipe 71 controlled by a valve 72 to a drainer 73 having a perforated bottom 74. In the drainer the bleach liquor is separated from the pulp which is then washed with water supplied through a perforated pipe 75. The bleaching liquor and the wash water are discharged through a pipe 76. When the washing has been completed, the pulp is flushed out of the drainer by water supplied through a pipe 77 and is delivered through a pipe 78 and pump 79 to a storage tank 80. Owing to the addition of water in flushing the drainer, the pulp in the storage tank 80 is much less concentrated, e. g., 2 to 3%. From

the storage tank the pulp is discharged through a pipe 81, pump 82 and pipe 83 to the head of the "riffler" 84 where it enters a box 85 and is mixed with water supplied through a pipe 86. Sufficient water is added to reduce the concentration preferably to approximately $\frac{3}{10}$ of 1%. The mixture of pulp and water overflows a baffle 87 and thence passes over baffles 88 and 89 onto a table which is covered with a suitable material, preferably a cotton felt having upwardly extending fibres which serve to catch the pulp fibre and permit separation thereof as the material flows over the table. Owing to the dilution and the action of the "riffler," any "fish eyes" present in the mass are dis-integrated, and the pulp is delivered to a box 90 at the end of the "riffler" and thence through a pipe 91 to the wet machine (not shown) where the water is again removed from the pulp. The pulp is thus reduced to a condition for use.

It is evident that instead of having a single midfeather dividing the tank into two compartments, I may employ a tank as shown in Fig. 5, in which there are two midfeathers 40, 41, extending longitudinally of the tank and dividing it into three compartments. In such case, the stock is caused to flow first through the outer compartments and then in the opposite direction through the middle compartment. The outer compartments are provided with worms 42, 43, similar to those described in connection with the tank illustrated in Fig. 1, and having similar short reverse worm sections 42^a and 43^a at their ends. The middle compartment is provided with longitudinally arranged worms 44, 45, which are of opposite pitch and are driven in opposite directions so as to force the stock received at one end of the compartment out from the other end thereof. These worms also have short reverse worm sections 44^a and 45^a at their ends. The two midfeathers 41, 40 are provided with ports or openings through which the shafts 46, 47 extend, and the said shafts are provided with short worm propellers of proper pitch so as to effect the passage of the stock from the outer compartments to the inner compartment or vice versa, and also to effect the thorough agitation and mixing of the pulp with the bleaching reagent. The inner compartment and the worms therein should be, of course, of such size as to accommodate and feed the stock which enters therein from the outer compartments.

The stock travels in one direction through the middle compartment and in the opposite direction in the outer compartments. This necessitates, of course, that the short worm propellers on each of the shafts 46, 47, shall be opposite in pitch. An advantage

is secured thereby inasmuch as the end thrust of the worm propellers on the shaft is neutralized, one by the other.

Instead of employing short transverse worm propellers, the apparatus may be made as shown in Fig. 4, in which said propellers are omitted. In this case the midfeather 50 has its ends spaced or separated from the end walls 51, 51, of the tank to leave passageways 52, 52. I utilize the longitudinally arranged worm propeller for circulating the body of the stock around the midfeather as shown by the arrows, but also so construct the worm conveyers or propellers that they shall have not only a feeding action but also an agitating or mixing action upon the stock. To this end, I employ in each compartment of the tank the two pairs of worm conveyers which are indicated as a whole at 53, 54. The shafts, on which these conveyers are formed or secured, are rotated in opposite directions by mechanism substantially as described in connection with Fig. 1. The propellers 53 are provided with blades 55, the function of which is to feed the body of stock in the direction of the arrows longitudinally of the compartments. Between these blades 55 the conveyers have blades 56 which are of opposite pitch to those at 55 and which are less in number, the function of which is partially to interrupt the flow and force the stock upwardly so as to effect a churning and agitating action thereon. The propellers 54 have blades 57 and 58 respectively arranged opposite the blades 55, 56, but of opposite pitch inasmuch as the shaft on which they are mounted rotates in the opposite direction to that in which the propeller 53 is bodily rotated.

In Figs. 7 and 8 of the drawings, a different form of bleacher is illustrated which may be employed in place of the bleachers previously described. The bleacher comprises a tank 92 preferably formed of tile-lined Portland cement or other suitable material which is not affected by the action of the bleach liquor and is preferably provided with a suitable cover. A midfeather 93 extends through the tank and is provided with openings 94 at opposite ends. Transverse shafts 95 are mounted in suitable bearings in the walls of the tank and are provided externally with driving means adapted to be actuated from any suitable source of power. The shafts 95 carry worms 96 which, when the shafts are actuated at relatively high speeds, serve to break up and agitate the pulp which is passing through the apparatus. Preferably short worms 97 are provided near the ends of the shafts 95 to prevent the material traversed from the opposite sides of the midfeather from piling up in the ends of

To ensure movement of the concentrated pulp mass through the tank, a conveyer is provided which may consist of a plurality of chains 98 driven by suitable sprockets 99 and 100, the former being mounted on shafts 101 supported in brackets 102 above the tank, and the latter being mounted on shafts 103 supported in bearings in the sides of the tank. The shafts 101 or 103 may be actuated from any suitable source of power to ensure the advance of the chains in the directions indicated by the arrows in Fig. 7. The chains form, therefore, a moving bottom for the tank which carries the concentrated pulp mass from one end to the other thereof. As the mass advances, the worms 96 churn the mass and pass it through the openings 94 in the midfeather. The continued circulation of the mass bodily advancing through the tank and intermittently agitating results in a thorough action of the bleaching reagent in a relatively short space of time in accordance with the principles of the invention.

It is possible, with an apparatus such as described, to considerably more than double the proportion of the pulp in the mixture, and it may be noted further that a pulp concentration of 6%, such as is customarily used, cannot be successfully treated in the apparatus described because of the fluid character of such a mass. The worm propellers in this case impede rather than facilitate the circulation. Instead of using a mixture containing 6% of the pulp, I employ a mixture containing from 10 to 25% of pulp, and consequently increase correspondingly the concentration of the calcium bisulphite in the aqueous solution. I am thus enabled to carry on the bleaching operation at a temperature not exceeding 75° to 80° F. The increased density of the mixture has the effect of lowering the resistance to the action of the bleaching reagent upon the fibers, especially those containing a high amount of color pigments, so that a more thorough bleaching is effected with consequent production of a whiter fibre. Moreover, the more gentle action of the reagent because of the lower temperature permits a greater yield of stronger fibre since the destruction of cellulose is practically negligible. Inasmuch as a smaller amount of water is required, and as the reaction is carried on at a lower temperature, much less water has to be heated, and I have attained in actual practice a reduction in the amount of fuel used to substantially one-eighth as much as is used in the former practice.

Various changes may be made in the details of the operation as hereinbefore described and within the scope of the accompanying claims without departing from the invention or sacrificing any of the advantages thereof.

I claim:

1. A method of bleaching pulp, which comprises mixing the pulp with a bleaching agent, the concentration of the pulp being such as to provide a substantially non-fluid mass, mechanically conveying the mass and subjecting it at intervals to agitation to ensure thorough commingling of the bleaching agent with the pulp. 5
- 10 2. A method of bleaching pulp, which comprises mixing the pulp with a bleaching agent, mechanically conveying the pulp mass in a closed circuit and subjecting it at intervals to agitation to ensure thorough 15 commingling of the bleaching agent with the pulp. 70
- 20 3. A method of bleaching pulp, which comprises mixing the pulp with a bleaching agent, mechanically conveying the pulp mass substantially without agitation, and subjecting it at intervals to agitation to ensure thorough 25 commingling of the bleaching agent with the pulp. 75
- 25 4. A method of bleaching pulp, which comprises mixing the pulp with a bleaching agent, the pulp forming more than 10 per cent of the mass, mechanically conveying the pulp mass and subjecting it at intervals to agitation to ensure thorough commingling 30 of the bleaching agent with the pulp. 80
- 30 5. A method of bleaching pulp, which comprises mixing the pulp with a bleaching agent, the pulp forming more than 10 per cent of the mass, mechanically conveying the 35 mass in a closed circuit and successively agitating the mass as it travels. 85
- 35 6. A method of bleaching pulp, which comprises mixing the pulp with a bleaching agent, maintaining the mass at a temperature not exceeding 80° F., mechanically conveying the mass in a closed circuit and successively agitating the mass during its travel. 90
- 40 7. A method of bleaching pulp, which comprises mixing the pulp with a bleaching agent and mechanically conveying the mass during the major portion of its travel, in a closed circuit. 95
- 45 8. A method of bleaching pulp, which comprises mechanically removing a portion of the moisture from the mass so that the mass will contain between 25 and 30 per cent of pulp, adding a proportion of a bleaching agent thereto and mechanically conveying the mass as it is subjected to the bleaching action. 100
- 50 9. A method of bleaching pulp which comprises mechanically removing a portion of moisture from the pulp, adding bleaching agent thereto and mechanically conveying the mass during a portion of its travel substantially without agitation, and agitating the mass to ensure thorough commingling of the bleaching agent with the pulp. 105
- 55 10. A method of bleaching pulp, which comprises mixing the pulp with a bleaching agent, the concentration of the pulp being more than 10 per cent, and subjecting the mass to a temperature not exceeding 80° F. 110
- 60 11. A method of bleaching pulp, which comprises mixing the pulp with a bleaching agent, the concentration of the pulp being substantially 115 18 per cent, and subjecting the mass to a temperature not exceeding 80° F. 120
- 65 12. A method of bleaching pulp, which comprises mixing the pulp with a bleaching agent, maintaining the mass at a temperature not exceeding 80° F., causing the mass to travel in a closed circuit and agitating the mass during its travel. 125
- 70 13. A method of bleaching pulp, which comprises mechanically removing a portion of the moisture from the pulp, adding a proportion of a bleaching agent thereto, and subjecting the mass to a temperature not exceeding 80° F. 130
- 75 14. A method of bleaching pulp, which comprises mechanically removing a portion of the moisture from the pulp, immediately adding bleaching agent thereto in proportion to provide a mass containing more than 10 per cent of pulp, and subjecting the mass to intermittent agitation to ensure thorough commingling of the bleaching agent with the pulp. 135
- 80 15. A method of bleaching pulp, which comprises subjecting the pulp to the action of a bleaching reagent, the concentration of the pulp being such as to provide a substantially non-fluid mass, and thereafter diluting the pulp to a low concentration to ensure separation of agglomerated fibre. 140
- 85 16. A method of bleaching pulp, which comprises subjecting the pulp to the action of a bleaching reagent, the concentration of the pulp being such as to provide a substantially non-fluid mass, diluting the pulp to a low concentration and passing it over riffles to ensure separation of agglomerated fibre. 145
- 90 17. Apparatus for bleaching paper pulp, comprising a tank having a midfeather dividing it into longitudinal compartments, and conveyors arranged longitudinally of said compartments for bodily conveying a mixture of pulp and bleaching reagent containing more than 10 per cent of pulp about said midfeather. 150
- 95 18. Apparatus for bleaching paper pulp, comprising a tank having a midfeather dividing it into longitudinal compartments, conveyors arranged longitudinally of said compartments for bodily conveying a mixture of pulp and bleaching reagent containing more than 10 per cent of pulp about said midfeather, and means at the ends of the midfeather for agitating and intermingling the components of said mixture. 155
- 100 19. Apparatus for bleaching paper pulp, 160

- comprising a tank having a midfeather dividing it into longitudinal compartments, the bottom of each compartment being formed with longitudinal grooves or beds, 5 and helical conveyers arranged in said grooves or beds for bodily conveying a mixture of pulp and bleaching reagent containing more than 10 per cent of pulp about said midfeather.
20. Apparatus for bleaching pulp, comprising a tank having a midfeather dividing said tank into longitudinal compartments, a pair of helical conveyers in each compartment, said conveyers having opposing blades 15 of opposite pitch, the conveyers in the two compartments being arranged to bodily convey a mixture of pulp and bleaching reagent containing more than 10 per cent of pulp in opposite directions so as to travel about 20 the midfeather, and means for rotating the conveyers.
21. Apparatus for bleaching pulp, comprising a tank having a midfeather dividing said tank into longitudinal compartments, a 25 pair of helical conveyers in each compartment, said conveyers having opposing blades of opposite pitch, the conveyers in the two compartments being arranged to bodily convey a mixture of pulp and bleaching reagent 30 containing more than 10 per cent of pulp in opposite directions so as to travel about the midfeather, and at least one of each said conveyers having blades opposite in pitch to the other blades thereof, to force 35 the stock oppositely.
22. Apparatus for bleaching pulp, comprising a tank having a longitudinal midfeather dividing it into longitudinal compartments, said midfeather having ports or 40 openings adjacent its ends, an agitator or propeller located in one of said openings, and means for rotating said agitator, in combination with means in said longitudinal compartments for bodily conveying a mixture of pulp and bleaching reagent containing more than 10 per cent of pulp about said 45 midfeather.
23. Apparatus for bleaching pulp, comprising a tank having a longitudinal midfeather dividing it into longitudinal compartments, said midfeather having ports or 50 openings adjacent its ends, an agitator or propeller located in each of said ports or openings to agitate the mixture passing therethrough, and conveyers arranged longitudinally of said compartments for bodily conveying a mixture of pulp and bleaching reagent containing more than 10 per cent of pulp about said midfeather.
24. Apparatus for bleaching pulp, comprising a tank having a longitudinal midfeather dividing it into longitudinal compartments, said midfeather having ports or 55 openings adjacent its ends, an agitator or propeller located in each of said ports or openings to agitate the mixture passing therethrough, helical conveyers arranged longitudinally of said compartments for bodily conveying a mixture of pulp and bleaching reagent containing more than 10 per cent of pulp about said midfeather.
25. Apparatus for bleaching pulp, comprising a tank having at least one longitudinal midfeather dividing it into longitudinal compartments, said midfeather or midfeathers having ports or openings adjacent the ends, at least one agitator or propeller located in each of said compartment, 60 said propellers having helical blades of the same pitch throughout the greater part of their length and having short helical portions of opposite pitch at the discharge ends 65 of the compartments adjacent the ports or openings.
26. In apparatus for bleaching pulp, at least one helical conveyor at the bottom of a pulp compartment for agitating and conveying the pulp therein, and short sections of the helical conveyor of opposite pitch adjacent the end of the compartment.

In testimony whereof I affix my signature.

ROBERT B. WOLF.
